(57) **CLAIM**

The ornamental design for a container body portion, as shown and described.

DESCRIPTION

FIG. 1 is a top, front, and right side perspective view of the present invention;

FIG. 2 is a front elevational view thereof, the right side, left side, and rear elevational views being identical except for the unclaimed environment;

FIG. 3 is a top plan view thereof; and,

FIG. 4 is a bottom plan view thereof.

The dash-dash-dash broken lines shown in the drawing views are included for the purpose of showing environmental structure that forms no part of the claimed design.

The dot-dash-dot-dash broken lines shown in the drawings represent the boundary lines of the claimed design.
